UNITED STATES PATENT OFFICE.

WILLIAM W. TUCK AND AUGUST WASSMANN, OF NEW YORK, N. Y.,
ASSIGNORS TO ABBOT AUGUSTUS LOW, OF SAME PLACE.

REVERSING-GEAR.

SPECIFICATION forming part of Letters Patent No. 663,372, dated December 4, 1900.

Application filed March 12, 1900. Serial No. 8,337. (No model.)

To all whom it may concern:

Be it known that we, WILLIAM W. TUCK, a resident of New York, borough of Brooklyn, county of Kings, and AUGUST WASSMANN, a resident of New York, (Astoria,) borough of Queens, county of Queens, State of New York, citizens of the United States of America, have invented an Improved Reversing-Gear, of which the following is a specification.

10 The object of our invention is to construct a simple and efficient reversing-gear such as shall be specially applicable for use on power-driven launches, automobiles, &c.

In the accompanying drawings, Figure 1 is 15 a longitudinal section of our reversing-gear. Fig. 2 is a plan view of part of the same on a somewhat-larger scale. Fig. 3 is a view looking in the direction of the arrow 1, Fig. 2; and Fig. 4 is an enlarged sectional view looking in the direction of the arrow 2, Fig. 2.

In the particular construction of our invention illustrated in the drawings the arrangement of shafting is such as would be used in applying the gear to a power-driven launch; but 25 it will be understood that our invention may be applied to other arrangements of shafting.

In the present instance, A is the driven shaft, to which rotary motion is applied from the motor, and Z is the shaft to be driven in one 30 direction or the other. This driven shaft Z is shown as provided with a bearing at X, while at the inner end z' it finds a bearing within the end of the driving-shaft A, but in such a way that the driven shaft Z can have 35 a short longitudinal motion imparted to it by any suitable means, as through a lever F, pivoted at f to a bracket on a fixed framework G, this lever F acting on a collar z, pinned or otherwise secured to the shaft Z.

40 To the end of the driving-shaft A is secured, by means of a nut a or otherwise, an inclosing casing consisting of a wheel B and a cylinder B', inclosing the gearing, hereinafter described. The wheel B and casing B' have 45 opposite internal conical friction-surfaces b and b'. Working in conjunction with these two conical clutching-surfaces are two friction-disks C and C', carried by and free to move endwise or longitudinally with the 50 movement of the shaft Z, so as to bring the disk C into frictional engagement with the surface b or to bring the disk C' into frictional engagement with the surface b', the

other disk being in each case free from engagement with its friction-surface. Of these 55 two clutching-disks one (marked C) is shrunk onto or otherwise firmly fixed to the shaft Z, so as to rotate with it, while the other disk, C', is free to turn upon a sleeve D, which in turn is loose or can rotate freely on this shaft Z, 60 but is held endwise in position against the hub of the disk C by means of a suitable collar d. The two friction-disks C and C' are geared together preferably through a pair of pinions 4 4, turning on radial pins 6, carried 65 by the hub of the sleeve D, and meshing with bevel-wheels 3 and 5, secured to or formed in one with their respective disks C and C'.

The sleeve D, which turns upon the shaft Z, extends out through an opening in the end 70 of the casing B' and has there secured to it, by means of keys e or otherwise, a brake-wheel E, which thus lies adjacent to the opening in the end of the inclosed casing through which the shaft Z passes. We prefer to form 75 a V-shaped groove in the periphery of this brake-wheel E and to employ in connection therewith a pair of brake-levers H and H', hinged together at h, Figs. 2 and 3. One of these brake-levers H is hinged to the cranked 80 or eccentric pin J, secured to a bracket on the frame by nuts j in such a way that it can be adjusted rotarily when necessary, Figs. 3 and 4. The corresponding end of the other lever H' is connected by a link h' to a lever 85 K, the pivot-pin of which passes through a vertical slot in a bracket g on the frame. The connections of the brake-levers H H' to the pin J and lever K are such as to allow the levers to move freely with the endwise 90 movement of the shaft Z and wheel E, as shown in Figs. 2 and 4. A set-screw k' can be ad-justed to act as an adjustable bearing-piece for the upper side of the pivot-pin k as may be desired, for in the operation of the device 95 when applying the brake-levers to the wheel E this pivot-pin k of the lever K will be forced up to a bearing against this set-screw k'. As shown in Fig. 4, the left-hand end of the lever K is connected by a link m (set at an angle, as shown) to lugs on the operating-lever F. To the outer end of this lever F is connected a rod f to move the driven shaft Z with its gear endwise in one direction or the other to reverse the motion. The parts may 100 be left in the midway position in which they

are shown in the drawings when the shaft Z is to be disengaged from connection with the shaft A.

When the shaft Z is to be driven in the same direction as the driving-shaft A, the lever F is operated to move the shaft Z endwise or longitudinally in the direction of the arrow 1, Fig. 1, to bring the disk C into firm frictional or driving contact with the wheel B. Under these conditions the shaft Z will be driven in the same direction and with the same speed as the shaft A. At the same time, the disk C' being then free from contact with the surface b' of the casing B' on the shaft A, this disk C' and the gearing will by simple friction run around idly in the same direction as and with the disk C.

When the shaft Z is to be driven in the opposite direction from that in which the shaft A is driven, endwise motion is imparted to the shaft Z in the direction of the arrow 2, Fig. 2, so as to free the clutch-disk C from the conical surface b of the wheel B on the shaft A and to bring the clutch C' into engagement with the conical surface b' of the casing B'. This same movement of the lever F, which has been employed to move the shaft Z endwise, will hold or brake the sleeve carrying the gear—that is, through the link m it will raise the corresponding end of the lever K, Fig. 4, and press its opposite end to cause the clamping-levers H and H' to grip the brake-wheel E, and hence stop the rotation of the sleeve D. Then the connections between the driving-shaft A and the driven shaft Z will be through the casing B', disk C', bevel-wheel 3, pinions 4, bevel-wheel 5, and disk C, which is fixed to the shaft Z, and consequently this shaft Z will then be driven in the opposite direction to that in which the shaft A is driven.

The link m forms a species of toggle connection, so that in moving it over from the position shown by full lines in Fig. 4 to that shown by dotted lines to apply the brake the clutch-disk C' will have full opportunity to make firm connection with the friction-face b' before the brake-levers are drawn home.

We claim as our invention—

50 1. A reversing-gear comprising a driving-shaft and a pair of clutching members carried thereby, in combination with a driven shaft, two friction-disks carried by said driven shaft and corresponding with said clutching members, one of said disks being fast on the driven shaft, gearing connecting said disks and means for braking or holding the gearing between the disks.

2. A reversing-gear comprising a driving-shaft and a pair of friction members carried thereby, in combination with a driven shaft, a pair of friction-disks carried by the driven shaft to engage with said members, a loose sleeve upon said driven shaft, one of said disks being fast on the shaft, means for braking the said sleeve and intermediate gearing between the said disks and carried by the said sleeve.

3. A reversing-gear comprising a driving-shaft, an inclosing casing thereon and internal conical clutching members carried by the 70 casing in combination with a driven shaft extending within said casing and a pair of friction-disks carried by the driven shaft within the casing to engage with the said conical members, one of said disks being fast to the 75 driven shaft and the other being loose thereon, intermediate gearing between the disks and means for braking or holding the said gearing.

4. A reversing-gear comprising a driving-shaft, an inclosing casing thereon and opposite internal clutching members carried by the casing, in combination with a driven shaft, a pair of clutching-disks carried by the driven shaft within said casing, one of said disks being fast to the driven shaft, a loose sleeve on the said shaft, gearing carried by the sleeve between the disks and a brake-wheel also carried by the sleeve outside the casing with braking means for said wheel, substantially as described. 80 85 90

5. The combination of a driving-shaft and driven shaft and reversing-gear therefor with a brake-wheel for the reversing-gear, a supporting-frame, a pair of clamping-levers for 95 the brake-wheel with an adjustable crank or eccentric pin for the support of one of the clamping-levers.

6. The combination of a driving and a driven shaft with intermediate reversing-gear 100 and a brake-wheel therefor with a lever to actuate the reversing-gear, clamping-levers to act on the brake-wheel, lever connections between the operating-lever and the clamping-levers and an adjustable bearing-piece for 105 said lever connections, substantially as described.

7. A reversing-gear comprising a driving-shaft and a pair of friction members thereon, in combination with a driven shaft, a pair of 110 friction-disks on the driven shaft to engage with said members, a sleeve loose upon the driven shaft and gearing carried by the sleeve between the two disks, one of which is fast upon the driven shaft and the other is loose 115 upon the sleeve, and means for braking said sleeve.

8. The combination of a driving and a driven shaft and reversing-gear with a brake-wheel therefor, a lever to operate the reversing-gear, clamping-levers to act on the brake-wheel and toggle-lever connections between the clamping-levers and the operating-lever, with an adjustable pivot for the lever of the toggle, as and for the purpose described. 120 125

In testimony whereof we have signed our names to this specification in the presence of two subscribing witnesses.
